GAS MODULATING AND SHUTOFF VALVE MECHANISM

Zdenek J. Lansky, North Riverside, and Gilbert Riske, Chicago, Ill., assignors to Stewart-Warner Corporation, Chicago, Ill., a corporation of Virginia

Application September 25, 1953, Serial No. 382,271

4 Claims. (Cl. 236—48)

The present invention relates to gas control valve mechanisms and is particularly concerned with the provision of an improved modulating and shutoff valve mechanism for controlling fuel gas supplied to a gas burner, especially of the type used for domestic space heaters, water heaters or for similar applications.

One of the objects of the present invention is to provide a single standard burner control device at low cost which can be adapted by simple adjustment to the following alternative applications: (1) snap on-snap off, in which the gas is turned either on or off with a snap action; (2) modulate gas flow down to a predetermined minimum and then snap off; and (3) modulate gas flow between a predetermined minimum and a predetermined maximum; all of these alternative modes of operation being under the control of its own thermostatic element.

Another object is to accomplish the above without the intervention of electrical means.

Still another object is to accomplish the above by means of novel mechanism which is rugged, but sufficiently sensitive to be directly actuated by a thermostatic element of the liquid filled bulb type.

Yet another object is to provide a novel and extremely simple mechanism for automatically shutting off the flow of gas through a modulating valve when the flow through the modulating valve has been decreased to some predetermined minimum, thereby insuring that there will be no gas flow under conditions where combustion might not be efficient or reliable.

Other objects and advantages will become apparent from the following description of a preferred embodiment of our invention.

Referring to the drawings, in which similar characters of reference refer to similar parts in both views:

Figure 1 is a diagrammatic representation of the working elements of a valve mechanism incorporating features of the present invention, shown in vertical medial section; and

Fig. 2 is a bottom view of a snap acting valve actuating element which is shown in section in Fig. 1. This view may be considered as taken in the direction of the arrows substantially along the line 2—2 of Fig. 1.

Gas burners, particularly gas burners for domestic space heating use, present a control problem since the systems and requirements are diverse. For instance it is frequently desirable to modulate the heat output according to requirements as determined by some thermostatic means; that is, to control heat output without turning the burner on and off unnecessarily. Arrangements for exercising a modulating control, however, usually are quite complex, since they of course cannot be predicated upon the simple opening or closing of a set of electrical contacts or upon any other arrangement which simply turns the burner on and off. There is a further problem in that gas burners will only operate between certain limits of gas flow—a maximum which cannot be exceeded without bringing about inefficient combustion or causing the flame to leave the burner and become extinguished, and a mini-

2

mum below which the burner also suffers from inefficiency and may cease functioning. Modulating arrangements, therefore, must either have some provision for shutting off the gas flow completely in the event that the flow rate has been modulated down below a predetermined minimum selected as appropriate for the particular burner with which the gas valve mechanism is to be used, or the burner must be modulated only between high and low limits which are satisfactory for that burner. With the latter system the burner is not automatically turned off and in a sense acts as its own pilot. A third system is one in which the burner is simply turned on and off as required.

The gas valve which forms the subject matter of the present invention takes into consideration these factors and provides a safe and economical solution to the problem, and accomplishes its function purely through the use of mechanical expedients, thereby making it feasible to operate and control the burner away from a source of electric power. By simple adjustment it can be adapted to give any of the control functions described above.

Referring now to the drawings, in Fig. 1 we have shown a housing indicated generally by the numeral 15 which is shown as being comprised of a main portion 12 to which a housing cover 14 is attached at the top. Openings which enter the bottom surface of the main portion 12 are closed by a bottom plate 16. This assembly contains the principal portions of the modulating and shutoff valve mechanism and receives fuel gas from an automatic pressure regulator 18 by way of a tube 20. Both the modulating and shutoff operation of the valve are under the control of a temperature sensitive liquid filled bulb 22 which ordinarily will be remotely located at some appropriate position and connected to the valve proper by a capillary tube 24. The automatic pressure regulator 18 portion of the apparatus is made up of a housing 26 having a gas inlet passage 28 which carries the fuel gas to a valve chamber 30 having a poppet valve seat 32 at its outlet. Restriction to flow through the valve seat 32 is afforded by a poppet valve 34 positioned within the chamber 30 and connected by a valve stem 36 to a flexible diaphragm 38 which is loaded in the upwardly direction by a coil spring 40. This spring is held in adjusted position by a threaded spring base 42 screwed into the lower end of the housing. The diaphragm 38 serves to close one side of a chamber 44 of comparatively large diameter which is in direct communication with the valve seat 32 and with the outlet gas connection previously referred to as indicated by the numeral 20.

When this portion of the apparatus is in operation with gas flowing to the inlet fitting 28 and from the outlet, any tendency for the gas to pass through the valve seat 32 into the chamber 44 at a rate higher than is necessary to maintain the appropriate pressure in the pipe 20 will cause a slight downward movement of the diaphragm 38 under the influence of this gas pressure. This tends to move the poppet 34 downwardly, thereby increasing the pressure drop across the valve seat 32. The result is that less gas flows into the chamber 44 and this reduces the pressure against the diaphragm with the result that the spring 40 moves the poppet 34 upwardly again slightly so as to increase the gas flow rate. So long as gas is flowing through the valve, the valve therefore functions automatically to maintain a predetermined pressure in the outlet line 20 which of course is lower than the pressure at the inlet fitting 28. By turning the threaded spring base 42 with a screw driver so as to shorten the spring 40, the gas pressure in the line

20 leading to the main regulator is increased. Conversely, backing off the plug 42 decreases the pressure in the line 20.

Gas passing to the main portion of the regulator by way of the pipe 20 enters a chamber 46 by way of an inlet port 48. The chamber is generally cylindrical in contour and is closed at a position above the port 48 by a flexible diaphragm 50. This diaphragm is maintained in place by an annular ring 52 having a central opening in alignment with and approximately the same diameter as the chamber 46. This ring 52 is in turn surmounted by a cover plate 54 having an opening 56 through the center thereof.

The diaphragm 50 is secured to an axially disposed valve stem 58 which extends upwardly through the opening 56 and downwardly beneath the diaphragm 50 for a considerable distance. Adjacent its upper end the stem 58 has a split ring 60 secured thereto which rests against the top face of the forked end of a horizontal beam 62, the forked end indicated at 64 straddling the stem 58. The beam 62 extends toward the left as seen in Fig. 1, and at its opposite end is pivoted to a horizontal hinge pin 66 such that as the forked end 64 rises and falls by pivoting the beam 62 about the hinge pin 66, the stem 58 rises and falls therewith, its downward movement being insured by a coil spring 68 which is disposed in the space between the upper surface of the diaphragm 50 and the lower surface of the cover plate 54 in a position concentric with the valve stem 58.

Beneath the diaphragm 50 the stem 58 is threaded to an adjustable bushing 70, the lower end of which is rounded so as to be self centering in a conical depression 72 in the top face of a poppet valve 74. This poppet serves to close an opening of comparatively large diameter through a valve seat indicated at 76. Because the valve seat is large, slight upward or downward movement of the poppet valve 74 will have a marked influence upon the rate of gas flow from the chamber 46 to the space 78 beneath the poppet valve 74 and in communication with the valve seat 76.

The poppet valve 74 is urged upwardly so as to seat the depression 72 against the rounded nose of the bushing 70 by a coil compression spring 80. This spring surrounds the stem 58 with its upper end bearing against the lower surface of the poppet valve 74 and its lower end supported by an annular ring 82 secured to the stem 58 in a position somewhat below the lower surface of the poppet valve 74. Below the spring base 82, the lower portion of the stem 58 is guided in a machined hole 84 passing through a bracket 85 which extends outwardly from the right hand wall of the chamber 78.

Gas in the chamber 78 passes downwardly and toward the left as seen in Fig. 1 and thence upwardly through a passage 86 to an outlet fitting 88. The passage 86 communicates with the chamber 78 by way of a downwardly facing valve seat 90. Directly beneath this valve seat 90 there is a cylindrical recess 92 of considerably larger diameter than the seat 90, which contains a lightweight ball valve member 94 of sufficient size to close the valve seat 90 when the ball 94 is in contact therewith. We prefer that the ball 94 be molded of a plastic material which is non-corrosive, light in weight, and which has a slightly resilient surface so as to form a good seal with the valve seat 90. For this purpose we have found molded nylon to be admirably suited. If desired, of course, an ordinary cup valve with a soft seat could be used in place of this ball.

The cylindrical chamber 92, which contains the ball 94, is connected near its bottom by a drilled passage 96 to the chamber 46 and the flow through this passage is regulated by means of a screwdriver set needle valve 98 located in the passage at any convenient position. The arrangement is such that as will appear, the flow of gas through the passage 96 and up around the ball 94 can be adjusted to float the ball upwardly until it is jammed

against the valve seat 90. Once in this position it will of course remain closed regardless of whether the valve 74 is opened or closed unless it is pushed from its seat by some means. This is because if the valve 74 is open, the pressure within the chamber 78 and therefore around the bottom of the valve 94 will be the same as the pressure in the line 20 which of course will be greater than the pressure at the outlet fitting 88. If the valve 74 is closed, the same result will be achieved if the needle valve is open because gas flowing through the passage 96 around the seat of the needle valve 98 will quickly equalize the pressures within the chambers 46 and 78. The needle valve 98 is provided so as to adjust the device to different conditions of operation as will appear presently.

In order to push the valve ball 94 away from its seat, a snap acting element 100 is provided, the structure of which may best be understood by a comparison of Figs. 1 and 2. At its right hand end as seen in these figures, the strip is secured by an anchor screw 102 in a position somewhat to the right of the lower end 104 of the valve stem 58. The strip extends toward the left from this position so that its opposite free end is somewhat beyond the ball 94. This free end is formed to provide a hole 106 of smaller diameter than the ball, which surrounds the ball, such that when this free end is in its upward position as shown in Fig. 1 the ball 94 is free to move upwardly against its seat 90, while if the free end of the strip 100 moves downwardly slightly, the ball will be caught in the hole 106 and moved downwardly away from its seat 90, thereby permitting gas to flow from the chamber 78 to the outlet 88.

Movement of the free end of the strip 100 is limited by an adjustment screw 108 which is threaded vertically into the housing so as to pass through an opening 110 in the strip 100 in a position just to the right of the hole 106. A portion of the adjustment screw 108 near its outer end is turned down to small diameter to form a pair of opposed shoulders 112 which are spaced apart an appropriate distance. As shown, the hole 110 in the strip 100 is substantially the same diameter as the screw 108, but is so positioned with respect to the hole for the anchoring screw 102 that when the hole 110 is slipped over the screw 108 to a position between the shoulders 112, the strip will need to be shifted slightly toward the left in order to secure the anchor screw 102. A portion of the strip to the right of the hole 110 is therefore brought between the shoulders 112 so that they effectively limit the upward and downward movements of the free end of the strip 100 to the positions set by turning the screw 108.

Referring principally to Fig. 2, it will be seen that much of the right hand half of the strip 100 is formed to provide a pair of parallel slots 114 near the edges which are connected somewhat to the left of the center of the strip by cutting out a generally rectangular piece. This provides a central tongue 116 which is integral with the strip 100 at and near the anchoring screw 102, but which has a free end 118 at about the center of the strip 100. Also, the free end of the strip 100 is connected to the anchored end at 102 by a pair of comparatively thin, flexible strips 120 at each edge.

The free end 118 of the tongue 116 is provided with an outwardly extending tab 122, which is directly opposite a similar tab 124 formed at the opposite end of the opening at the center of the strip. These two tabs 122 and 124 extend through openings in a semicircular spring metal member 126 which tends to straighten out to a larger diameter. It therefore exerts a compressive force acting between the free end of the tongue 118 and the main portion of the strip 100 at the base of the tab 124.

The lower end 104 of the valve stem 58 rests against the tongue 118 in a position slightly to the left of the anchoring screw 102 and, therefore, as the valve stem 58 descends and pushes the free end 118 of the tongue 116

downwardly, a position is eventually reached where the free end 118 passes below the plane of the spring base at the root of the tab 124. When this happens, the compressive force of the spring 126 snaps the free end of the blade upwardly, thereby releasing the ball 94. This, as previously indicated and as will be more fully explained, permits the ball 94 to close the valve opening at the seat 90 under certain circumstances. Conversely, as the valve stem 58 rises to a certain predetermined position, the rising spring base at the tab 122 will cause the compression spring 126 to snap the free end of the blade 100 downwardly, thereby pushing the ball valve 94 away from its seat 90 and preventing it from reseating.

Just to the right of the pivot pin 66 the beam 62 has a generally spherical socket 130 formed therein in its upper surface. Directly beneath this socket the beam 62 is urged upwardly by a coiled compression spring 132 which exerts sufficient force to lift the valve stem 58 against the compressive force of the coiled spring 68 so as to open the poppet valve 74 unless the spring 132 is restrained.

In a position above the beam 62 a corrugated metal bellows chamber 134 is located with a rounded nose 136 at its lower end in the socket 130, and with a socket 138 at its upper end embracing the conical end of an adjustment screw 140. This adjustment screw is in vertical alignment with the socket 130. The interior of the bellows 134 is connected to a capillary tube 142 which has a few turns disposed within the space about the bellows 134 to give greater flexibility and which extends outside this space to become the previously identified tube 24 connected to the temperature sensitive bulb 22. The bulb 22, tube 24—142 and bellows 134 form a sealed hydraulic system which is filled with a liquid having a high temperature coefficient of expansion.

The adjustment screw 140 is threaded axially through a bushing 144 which in turn is provided with external threads 146 threaded through the top 148 of the valve housing cover 14. The bushing 144 is also drilled and tapped radially to provide for a setscrew 150 which can be tightened to secure the adjustment screw 140 against rotation relative to the bushing 144. The setscrew 150 also extends outwardly sufficiently beyond the surface of the bushing so that as shown, when the bushing 144 is rotated sufficiently in either direction, the setscrew 150 impinges against a stop pin 152 so as to limit rotation of the bushing 144 to something less than one full turn. The upper end of the bushing 144 is secured to a slip-on or setscrew secured control knob 154 which may be of the type used on electronic equipment.

With this arrangement, the knob 154 can be removed from the upper end of the bushing 144 and the bushing rotated to some predetermined position such as with the setscrew 150 against the stop pin 152 for instance. Thereafter the setscrew 150 can be loosened slightly and through the use of a screwdriver the adjustment screw 140 can be rotated inwardly or outwardly to preset the starting position for the bellows 134. During this adjustment the bushing 144 is restrained against rotation. Once the starting position has been accurately adjusted, the setscrew 150 is tightened and the knob 154 replaced. Thereafter, turning the knob 154 throughout its range of motion (as limited by the setscrew 150 and stop pin 152) will cause the bushing 144 to move inwardly or outwardly slightly as determined by the pitch of the threads 146. Ordinarily the knob 154 will carry some indicia so as to permit the user to set the valve to whatever temperature it is desired to maintain. This will usually take the form of a temperature scale which may conveniently extend from 55° F. to 85° F., or so.

As the temperature of the bulb 22 rises, the liquid therein will expand and this expansion will be communicated to the bellows 134 by way of the capillary tube 24. This will cause the bellows 134 to elongate slightly so that the nose 136 of the bellows, operating in the socket

130, will cause the forked end 64 of the lever 62 to be moved downwardly a considerably greater amount since the distance between the pivot 66 and the valve stem 58 is great as compared with the distance between the pivot 5 and the socket 130. This releases the support from beneath the collar 60 and permits the spring 68 to urge the poppet valve 74 downwardly so as to reduce the clearance between the valve poppet and its seat 76. Conversely, decrease in the temperature of the bulb 22 produces opening movement of the valve poppet 74.

The above described valve mechanism can be adjusted to effect three types of burner control, depending upon the conditions of the particular installation.

Assuming that the system is connected between a source 15 of gas supply and a burner and that it is desired to adjust the system such that the control effected is of the snap-on, snap-off type, this is accomplished in the following fashion: First of all the pressure regulator 18 is so adjusted as to supply the quantity of gas through the system to the burner desirable for full burner operation. Then the needle valve is so adjusted that the flow of gas through the passage 96 is sufficient to float the ball valve element 94 upwardly against the spring 100 when downward movement of the poppet valve 74 is just beginning 25 to exert a throttling effect upon the gas supply through the valve seat 76. It will be appreciated that as the poppet valve 74 exerts a throttling effect upon the main stream, the flow rate through the bypass 96 will increase. The original adjustment of the position of the round ended bushing 70 relative to the lower end of the stem 58 is then such that upon slight additional downward movement of the valve stem 58 the free end of the spring 100 30 will be snapped to the "up" position, thereby permitting the ball valve element 94 to float upwardly and jam in 35 its valve seat.

Upon cooling of the thermostatic bulb 22, the valve stem 58 will rise until the free end of the spring 100 is snapped downwardly, thereby pushing the valve ball 94 away from its seat and permitting a full rate of flow 40 of gas through the valve mechanism.

If it is desired to adjust the apparatus to modulate the gas flow between a predetermined maximum and a predetermined minimum and then to snap off the gas flow below that minimum, the following procedure is used: 45 As in the previous example, the pressure regulator 18 is so adjusted as to determine the maximum flow rate through the valve system. The needle valve 98 is then screwed all the way in so as to shut off the flow of gas through the bypass 96. With the bulb 22 warm, the knob 154 is rotated until the poppet valve 47 has been closed sufficiently to give the minimum desired flow rate 50 through the valve seat 76. Under these conditions the valve stem 58 will have moved downwardly somewhat more than enough to cause the free end of the spring member 100 to snap upwardly. If necessary, the position 55 of the bushing 70 upon the stem 58 can be shifted to insure this. The needle valve 98 is then backed off until the flow rate through the bypass 96 when the poppet valve is in the last described position, is just sufficient 60 to float the valve ball 94 upwardly so that it jams in its seat.

With the system adjusted as just outlined, increase in temperature at the bulb 22 will cause the valve stem 58 to move downwardly until the gas supplied to the appliance 65 has been throttled to a flow rate near the desired minimum; at this juncture the free end of the spring 100 will snap upwardly. Upon somewhat further downward movement of the valve stem 58, the valve ball 94 will float upwardly and jam in its seat, thereby shutting off 70 the appliance burner. Upon cooling of the bulb 22 the valve stem 58 will rise until the free end of the spring blade 100 snaps downward, thereby pushing the ball valve 94 away from its seat and establishing gas flow to the appliance. It will be seen that the burner will be shut off at the minimum desired flow rate, and will be turned 75

back on at a somewhat higher rate. Note also that this differential is adjustable since flow through the bypass determines the off point while the snapping point of the blade 100 determines the conditions under which the burner is turned on. This is desirable since a burner in operation will usually function safely at a lower gas rate than it takes to start the burner in operation and different burners will differ in this characteristic.

To adjust the mechanism to modulate between a fixed upper and a fixed lower limit, but without shutting off the appliance at the lower limit, the pressure regulator 18 is adjusted as previously described to establish the maximum flow rate to the appliance. The ball 94 is removed from the device and the needle valve 98 is unscrewed sufficiently to give the minimum desired flow rate through the passage 96 when the poppet valve 74 is closed. Thus, the poppet valve 74 moves upwardly and downwardly under control of the thermostatic bulb 22 to give a modulating control which cannot be greater than that present at the regulator 18 and which cannot be less than the amount which will pass through the passage 96. Since the ball valve 94 has been removed, the snap acting leaf 100 has no effect upon the functioning of the mechanism.

From the above description of a preferred embodiment of our invention it will be seen that variations and modifications in the structure can be made without departing from the scope and spirit of the invention and therefore the invention is to be measured by the scope of the following claims.

We claim:

1. A gas control valve comprising means forming an adjustable modulating valve having a movable element the position of which determines the rate of gas flow through said valve, a thermostatic element connected for moving said movable element, a check valve connected in series flow relationship to said modulating valve, means forming a gas bypass around said modulating valve for closing said check valve when the flow rate through said bypass exceeds a predetermined amount, a snap acting element adapted for holding said check valve open when in one position and for permitting said check valve to close when in a second position, said snap acting element being arranged to be actuated to said one position by said movable element whenever said modulating valve is opened more than a predetermined amount and to be actuated to said second position whenever said modulating valve is closed more than substantially said predetermined amount, and adjustable restrictor means interposed in said bypass to preset the pressure differential across said modulating valve which is necessary to produce said predetermined flow rate through said bypass.

2. A gas control valve comprising means forming a modulating valve for regulating the flow of gas therethrough according to the temperature of a thermostatic element, a snap acting mechanism connected to be operated by said modulating valve so as to be snapped in one direction when said modulating valve is closed more than a predetermined amount and to be snapped in the opposite direction when said modulating valve is opened more than said predetermined amount, a check valve downstream of said modulating valve having a movable valve element and a seat, said snap acting means being adapted when snapped in said one direction to release said movable valve element and when snapped in said opposite direction to hold said movable valve element away from its seat to permit flow through said modulating valve and said check valve, and means forming a bypass connected

between the upstream side of said modulating valve and a position adjacent the upstream side of said movable valve element such that flow through said bypass will blow said movable valve element against its seat when 5 said modulating valve is closed a predetermined amount, and means for regulating the flow rate through said bypass.

3. A gas control valve comprising means forming a modulating valve for regulating the flow of gas therethrough according to the temperature of a thermostatic element, a snap acting mechanism connected to be operated by said modulating valve so as to be snapped in one direction when said modulating valve is closed more than a predetermined amount and to be snapped in the opposite direction when said modulating valve is opened more than said predetermined amount, a check valve downstream of said modulating valve having a light-weight ball movable out of a depression and against a valve seat, said snap acting means being adapted when snapped in said one direction to release said ball and when snapped in said opposite direction to push said ball away from said seat and into said depression to permit flow through said modulating valve and said check valve, and means forming a bypass connected between the upstream side of said modulating valve and a position in said depression so that gas flowing through said bypass will float said ball out of said depression and against said seat, and means for regulating the flow rate through said bypass.

25 4. A gas control valve comprising means forming an adjustable modulating valve having a movable element the position of which determines the rate of gas flow through said modulating valve, a thermostatic liquid filled bulb and bellows mechanism having a member movable upon changes in temperature of said bulb, motion multiplying means connecting said movable member to said movable element to cause opening and closing movement of said modulating valve as said bulb cools and warms respectively, an on-off valve comprising a movable member and a valve seat connected in series flow relationship downstream of said modulating valve, snap acting mechanism for holding said movable member away from its seat when snapped in one direction and for conditioning said movable member for closing when snapped in the opposite direction, said snap acting mechanism being actuated in said one direction by said movable element during opening movement of said modulating valve when said modulating valve has reached a predetermined position and being actuated in said opposite direction by said movable element during closing movement of said modulating valve when said modulating valve has reached a predetermined position, means forming a bypass around said modulating valve for closing said on-off valve when the flow rate through 40 said bypass reaches a predetermined level, means for adjusting the position at which said movable element actuates said snap acting mechanism and means for adjusting the flow rate through said bypass.
